METHOD OF AND APPARATUS FOR
UNITING MESH FABRICS

Charles Seaman, Jamaica Estates, N. Y.

Application June 16, 1943, Serial No. 490,991

18 Claims. (Cl. 112—2)

This invention relates to sewing machines, and more particularly to an attachment for a zig-zag sewing machine, as well as a method of joining two pieces of mesh fabric together.

For many uses today, it is highly desirable that mesh fabric be of relatively wide widths. However, many mesh fabric machines do not produce a mesh fabric of the desired width. Thus, to provide a mesh fabric of relatively large width, it becomes necessary to join two pieces of such mesh fabric by sewing together the opposite edges of the mesh fabric to produce a seam with each of the original pieces of the mesh fabric extending in opposite directions therefrom. It is highly desirable to align the opposite edges of the respective pieces of the mesh material which are to be stitched together so that the interstices adjacent the seam are in substantially matching relation, and produce a smooth flat seam as well as impart to the seamed material a general appearance at least of a single piece of mesh fabric.

An object of this invention is to provide a method which comprises aligning two pieces of mesh fabric with two opposite edges in abutting relationship and securing said edges together by a zig-zag stitching.

Another object of this invention is to provide a zig-zag sewing machine with means to align the opposite edges of two pieces of mesh fabric and feed the aligned materials to and through the stitching position where the edges will be joined together by zig-zag stitching.

A further object of this invention is to provide an attachment for a zig-zag sewing machine, having means which will properly position the opposite edges of the two pieces of mesh material which are to be joined together and permit feeding of the thus-positioned materials through the stitching position where the edges will be joined together in abutting relationship by zig-zag stitching.

Other objects will become apparent from the following description.

In general, the objects of this invention are accomplished by providing a zig-zag sewing machine before the stitching position with a roll having a plurality of projections arranged circumferentially thereof and so positioned as to simultaneously and progressively engage the interstices adjacent the longitudinal edges of two pieces of mesh fabric extending in opposite directions and position the opposite edges in substantially abutting relationship and align the interstices of the two fabrics in substantially matching relationship. Means are provided to guide the two pieces of mesh material to and from the aligning roll. Means are also provided to inhibit the overlapping of the edges of the respective

materials prior and subsequent to the passage of the two materials over the aligning roll.

The aligning roll may be rotated by the mesh fabrics passing thereover. Preferably, the aligning roll is driven by means operatively connected to the pulley drive of the machine.

The nature of the invention will become more apparent from the following description when taken in conjunction with the accompanying drawings, wherein:

Figure 1 is a top plan view of a sewing machine, the head of which is partly broken away for clarity, showing one embodiment of the attachment in position;

Figure 2 is a perspective view of the attachment and driving means therefor;

Figure 3 is a section taken on the line 3—3 of Figure 1;

Figure 4 is a section taken on the line 4—4 of Figure 1; and

Figure 5 is a plan view of two pieces of mesh fabric joined together.

Referring now to the drawings, wherein like reference numerals designate like parts, the reference numeral 10 designates a base upon which is supported a sewing machine head 12. At one end thereof, the head 12 is provided with a needle bar 14 in which a needle 16 is positioned and a presser foot bar 18 which carries a presser foot 20. The sewing machine is of the well-known type designed to sew material with the so-called zig-zag stitch. In such a machine, the needle bar 14 is reciprocated in a vertical direction and after each penetrating thrust is oscillated horizontally whereby the needle stitches first on one side and then on the other side of a seam to provide the zig-zag stitching. The precise details of the mechanism for horizontally oscillating and vertically reciprocating the needle bar are well known in the art and, since they form no essential part of this invention, it is unnecessary to give a detailed description thereof.

The presser foot 20 cooperates with feed dogs 22 which extend through apertures 24 of a cover plate 26. The feed dogs 22 are actuated by the well-known feed-actuating mechanism (not shown). A hand lever 28 is provided for manual elevation or lowering of the presser foot bar 18.

At the other end of the head 12, there is provided a pulley 30 driven by means of a belt 32 by a suitable drive mechanism (not shown). The pulley 30 drives the main shaft (not shown) for actuating the needle bar. It is to be noted that the pulley and the drive means therefor are on one end of the machine, and the needle bar 14 and presser foot bar 18 are on the opposite end thereof. The details of the sewing machine described up to now are of the conventional zig-zag sewing machine type.

60 The attachment which comprises one phase of

the instant invention will now be described. As shown in Figures 1 and 2, the attachment comprises a base 40 which is removably secured by screws 42 to the work support 44 of the machine. At each end, the attachment base 40 is provided with upwardly inclined arms 46 and 47, and the upper free end of each arm is provided with a bearing, 48 and 49 respectively, in which a shaft 50 is rotatably mounted. Intermediate the bearings 48 and 49, a roll 52 is secured to the shaft by means of a set screw 54. As fully shown in Figures 1, 2 and 3 of the drawings, the roll 52 is provided with a plurality of projections 56 arranged circumferentially of the roll and positioned thereon in accordance with the pattern of the mesh fabrics passed over the roll 52. In the form shown, there are two sets of projections, each set being laterally spaced from the other so that when two mesh fabrics to be joined are fed over the roll 52, each set will progressively engage the (full) successive interstices adjacent the edges of the respective mesh fabrics passing thereover and align the two fabrics so that the interstices are in substantially matching relationship and the edges are in substantially abutting relationship. In the form shown, the projections of one set are disposed in staggered relationship with respect to the projections of the other set.

A roll 69 provided with a hub 62 is also secured to the shaft 50 by means of a set screw 64. As shown in Figure 1, the roll 69 is adjacent (to the left) the bearing 48. A roll 66 provided with a hub 68 is secured to the shaft 50 by means of a set screw 70. As shown in Figure 1, the roll 66 is positioned on that end of the shaft 50 which extends through the bearing 49.

The mesh fabrics are passed over the roll 52 so that the projections 56 will align the fabrics, as previously mentioned. The rolls 60 and 66 engage the mesh material at places removed from the projections 56 and aid in supporting and feeding the material over the roll 52.

In order to guide the two pieces of mesh material fed to the roll 52, there is provided a guide 74 which is positioned in advance of the roll. The guide 74 is provided with a separator blade 76 which is positioned on a line intermediate the two sets of projections 56 and is designed to prevent overlapping of the two edges of mesh material fed thereunder. As shown in Figure 1, the guide 74 consists of a bar having one end thereof looped inwardly, as designated by the reference numeral 78, in order to prevent any straight edges from contacting the mesh fabric passing therebeneath. The other end of the guide 74 is secured in one end of an arm 80 by means of a screw 82. The other end 84 of the arm 80 is mounted on a sleeve 86 loosely positioned on the shaft 50. A spring 88, positioned intermediate a flange 90 and the end 84 of the arm 80, urges the guide 74 downwardly. Due to the spring 88, the guide is resiliently mounted.

In order to guide the mesh fabrics from the roll 52, there is provided a guide 94 which is positioned beyond the roll 52 and in advance of the stitching position. The guide 94 comprises a vertical member 96, bent at the top thereof to form a horizontal member 98 which is adjustably mounted in a sleeve 100 by means of set screws 102. The lower end of the vertical member 96 is bent to form a horizontally extending W-shaped member 103 beneath which mesh material passes. It is to be noted that each of the

mesh fabrics passing under the member 103 is engaged only at one point.

The two guides 74 and 94 serve to guide the mesh fabrics to and from the roll 52. By adjusting the guide 94, the arc of contact between the fabrics and the roll 52 may be increased or decreased as desired.

In advance of the guide 94, there is provided another guide 104 beneath which the materials pass in their travel to the stitching position. The guide 104 is provided with a blade 106 which is designed to maintain the longitudinal edges of the mesh materials in position and prevent them from overlapping. The guide 104 is carried on one end of an arm 108, the other end 110 of which is pivotally mounted in a block 112 adjustably secured on the presser foot bar 18 by means of a set screw 114. The guide 104 is yieldably mounted by means of a spring 116 secured at one end thereof to a pin 118 on the arm 108, the other end of the spring being secured to a pin 120 on the block 112. The guide 104 preferably is positioned to cooperate with the work support and flatten, if necessary, the two materials passing thereunder, especially in the neighborhood of the longitudinal edges to be joined.

The guide 104 is also positioned in close proximity to the presser foot 20. As shown in Figures 1 and 3, the blade 106 extends in between the bifurcated toes of the presser foot. The blade 106 is beveled in shape and a portion thereof extends between the bifurcated toes of the presser foot. As previously mentioned, it serves to prevent the longitudinal edges of the aligned materials from overlapping.

A roll 122 is positioned rearwardly of the stitching position and it is designed to engage the seamed materials at the seam thereof and cooperate with the work support in feeding the seamed materials across the work support. The roll 122 is secured to a sleeve 124 which, in turn, is secured to a shaft 126. The roll 122 is provided with a hub 128 which is secured to one end of a vertical arm 129 of the member 130. The member 130 is also provided with a horizontal arm 131, one end of which is integral with the vertical arm 129. The horizontal arm 131 extends through a block 132 and is secured therein by means of a set screw 134. The block 132 is slidably disposed on the presser foot bar 18 and is seated on the block 112. The portion of the arm 131 extending beyond the block 132 is secured in the sleeve 100 by means of screws 136. In this manner, the arm 131 carries the sleeve 100 in which the guide 94 is positioned. Upon elevation of the presser foot bar 18, the block 112 will be raised, and the guide 104 and the block 132 will be accordingly raised. Elevation of the block 132 also elevates the guide 94 and the roll 122.

The roll 122 is driven by the shaft 126 through the mechanism of the general type disclosed in my copending applications Serial Nos. 481,971 and 481,972, both filed April 6, 1943, and which will now be briefly described.

The shaft 126, which is spaced from the work support, is disposed rearwardly of the head and driven from the pulley 30 of the machine. As shown in Figure 1, a pulley 140 is secured to the main drive pulley 30 in any suitable manner. The pulley 140 drives a belt 142 formed of an elastic material, such as rubber, and trained over a pulley 144 positioned on one end of a shaft 146 positioned rearwardly of the head. The shaft 146

is journaled in an arm 148 of a bifurcated block 150 mounted at the rear of the sewing machine head. The other end of the shaft 146 is journaled in the other arm 152 of the block 150. Adjacent the arm 152, the shaft 146 is provided with a gear 154 which meshes with a gear 156 mounted on a stub shaft 158 carried by the arm 152. A gear 160 on the stub shaft 158 meshes with a gear 162 carried on the end of the shaft 126 and journaled in the arm 152. From the description, it is clear that the arm 152 constitutes a bearing for the shaft 126, and the gears 154, 156, 160, 162 serve as a reducing gear train, and by proper selection of the gears any appropriate speed may be imparted to the shaft 126. If desired, the arm 152 and the gear train may be encased in a cover (not shown). It will thus be seen that when the machine is operated, the shaft 126 will be operated and the roll 122 will be driven in timed relationship with the feed dogs as the stitching operation progresses.

The block 150 is provided with a pair of spaced depending lugs 170, through which a pivot shaft 172 extends and in which the pivot shaft 172 is secured. The opposite ends of the pivot shaft 172 pass through ears 174 and 176 of arms 178 and 180 respectively of a base 182, the horizontal member 184 of which is removably secured to the work support by means of screws 186. A spring 188 positioned on the pivot shaft 172 urges the block 150 downwardly.

From the preceding description, it is apparent that as the stitching operation progresses, the roll 122 will engage the seam as the material passes from the stitching position and feed the seamed material across the work support to prevent accumulations of the stitched material.

When the seamed material is relatively wide, a roll 190 may be mounted on the sleeve 124 to aid in preventing accumulations alongside of the work support laterally of the needle. The roll 190 is of the form and construction described in my copending application Serial No. 481,972 (see Figure 8).

When the roll 122 is elevated, the roll 190 will also be elevated, and the block 150 together with the appurtenant elements thereof will be moved about the pivot shaft 172.

The roll 52 may be driven by the material passing thereover as it is being fed to and through the stitching position previously mentioned. Alternatively, the shaft 50 may be driven from the shaft 126, and such an embodiment is shown in Figures 1 and 2. Referring now to these Figures 1 and 2, a pulley 196 is secured to the shaft 126 adjacent the arm 152. An elastic belt 198, driven by the pulley 196, drives a pulley 200 which is loosely mounted on the shaft 50. The pulley 200 can be moved into locking position with a clutch mechanism 202 secured to the shaft 50.

The roll 52 is made of any smooth-surfaced material. A roll made of polished or coated wood has given satisfactory results. The projections 56 are made of any material which has a smooth surface so that they will not injure the fabric when the meshes thereof are engaged thereby. Projections made of polished metal or smooth-surface plastic have given satisfactory results. The rolls 60, 66 and 122 are surfaced with materials which will produce the desired tractive effect. When such rolls are surfaced with cork, satisfactory results are obtained.

The projections may be made integral with the roll or may be separately made and positioned in place on the roll. Preferably, the projections are

made conical in shape so that they can be used with various sized interstices without change. Though one set of projections has been shown for each of the two pieces of mesh fabric, it is to be understood that a plurality of sets for each fabric may be used. Of course, when such a plurality of sets of projections are used, they are also arranged in accordance with the pattern of the interstices, which is generally staggered.

In operation, two pieces of mesh material 210 and 212 are fed beneath the guide 74 with the opposite edges 214 and 216 engaging the respective side of the separator 76, and pass therefrom upwardly over the roll 52. Each projection 56 of one set penetrates into the respective interstices 215 of the fabric 210 as the fabric passes thereover. Each projection of the other set penetrates into the respective interstices 217 adjacent the edge of the piece 212. The rolls 60 and 66 aid in feeding material during the period it is in contact with the roll 52. The projections 56 align the mesh fabric in substantially matching relationship, and the two pieces of aligned mesh fabric pass beneath the guide 94. The guides 74 and 94 serve to provide the necessary arc of contact between the mesh fabrics and the roll 52. Upon leaving the guide 94, the aligned materials pass beneath the guide 104, the separator 106 serving to prevent the aligned materials from overlapping. In this condition, the materials are fed through the stitching position whereby the zig-zag stitching 218 is produced and the two materials are joined together. It is to be noted that the edges 214 and 216 are in abutting relationship. The roll 122 engages the seamed material at the seam thereof and aids in feeding the seamed material after the seaming operation. The roll 190 also aids in preventing accumulations on the machine laterally thereof.

From the foregoing description, it is apparent that the instant invention provides an attachment for positioning the opposite edges of two pieces of mesh material in abutting relationship for stitching and for presenting the thus-positioned edges to the stitching position, as well as aligning the two fabrics with the interstices thereof in substantially matching relationship. The attachment may be secured to a zig-zag machine without in any way damaging the machine or without any great effort. When the attachment is not desired, it may be removed from the machine by removing the screws 42 which secure the base of the attachment to the work support. Likewise, the attachment is so constructed that it may be driven by the material passing thereover, or directly from the main driving pulley of the machine. When the shaft 50 is driven by the main pulley of the machine, the speeds are, of course, adjusted so as to feed the material in timed relationship with the stitching operation and the feed dogs. As previously explained, the driving mechanism, which incidentally also drives the rolls 122 and 190, may be moved to inoperative position.

Since it is obvious that various changes and modifications may be made in the above description without departing from the nature or spirit thereof, this invention is not restricted thereto except as set forth in the appended claims.

I claim:

1. In combination with a zig-zag sewing machine for joining two pieces of mesh fabric together at the longitudinal edges thereof with the pieces extending in opposite directions from the seam, means to progressively engage the inter-

stices adjacent the respective edge of each piece of fabric and align said pieces with said edges in substantially abutting relationship, means to feed the thus-aligned materials with the edges thereof in position for zig-zag stitching, and means before and after the aligning means to inhibit overlapping of the two fabrics at the edges thereof.

2. In combination with a zig-zag sewing machine for joining two pieces of mesh fabric together at the longitudinal edges thereof with the pieces extending in opposite directions from the seam, a rotatably mounted roll over which both pieces of said mesh fabric simultaneously pass in their travel to the stitching position, said roll having a plurality of projections circumferentially thereof and positioned in accordance with the pattern of the interstices of the fabrics to progressively engage the interstices adjacent the respective edge of each piece of fabric and align said pieces with said edges in substantially abutting relationship, and means to feed the thus-aligned materials with the edges thereof in position for zig-zag stitching.

3. In combination with a zig-zag sewing machine for joining two pieces of mesh fabric together at the longitudinal edges thereof with the pieces extending in opposite directions from the seam, a rotatably mounted roll over which both pieces of said mesh fabric simultaneously pass in their travel to the stitching position, said roll having a plurality of projections circumferentially thereof and positioned in accordance with the pattern of the interstices of the fabrics to progressively engage the interstices adjacent the respective edge of each piece of fabric and align said pieces with said edges in substantially abutting relationship, means to feed the thus-aligned materials with the edges thereof in position for zig-zag stitching, and means to inhibit overlapping of the two fabrics at the edges thereof.

4. In combination with a zig-zag sewing machine for joining two pieces of mesh fabric together at the longitudinal edges thereof with the pieces extending in opposite directions from the seam, a rotatably mounted roll over which both pieces of said mesh fabric simultaneously pass in their travel to the stitching position, said roll having a plurality of projections circumferentially thereof and positioned in accordance with the pattern of the interstices of the fabrics fed thereover to progressively engage the interstices adjacent the respective edge of each piece of fabric and align said pieces with said edges in substantially abutting relationship, means to feed the thus-aligned materials with the edges thereof in position for zig-zag stitching, and guide means before and after said roll to maintain the fabrics in contact with said roll.

5. In combination with a zig-zag sewing machine for joining two pieces of mesh fabric together at the longitudinal edges thereof with the pieces extending in opposite directions from the seam, a roll having a plurality of projections circumferentially thereof and positioned in accordance with the pattern of the interstices of the fabrics fed thereover to progressively engage the interstices adjacent the respective edge of each piece of fabric and align said pieces with said edges in substantially abutting relationship, means to feed the thus-aligned materials with the edges thereof in position for zig-zag stitching, and means before and after said roll to inhibit the edges of the fabrics from overlapping.

6. In combination with a zig-zag sewing machine for joining two pieces of mesh fabric to-

gether at the longitudinal edges thereof with the pieces extending in opposite directions from the seam, a rotatably mounted roll over which both pieces of said mesh fabric simultaneously pass in their travel to the stitching position, said roll having a plurality of projections circumferentially thereof and positioned in accordance with the pattern of the interstices of the fabrics to progressively engage the interstices adjacent the respective edge of each piece of fabric and align said pieces with said edges in substantially abutting relationship, means to drive the aligning roll from the pulley end of said machine, means to render said driving means inoperative for driving said aligning roll, and means to feed the thus-aligned materials with the edges thereof in position for zig-zag stitching.

7. In combination with a zig-zag sewing machine for joining two pieces of mesh fabric together at the longitudinal edges thereof with the pieces extending in opposite directions from the seam, a rotatably mounted roll over which both pieces of said mesh fabric simultaneously pass in their travel to the stitching position, said roll having a plurality of projections circumferentially thereof and positioned in accordance with the pattern of the interstices of the fabrics to progressively engage the interstices adjacent the respective edge of each piece of fabric and align said pieces with said edges in substantially abutting relationship, means to drive the aligning roll from the pulley end of said machine, means to render said driving means inoperative for driving said aligning roll, means to feed the thus-aligned materials with the edges thereof in position for zig-zag stitching, and means to inhibit overlapping of the two fabrics at the edges thereof.

8. For a zig-zag sewing machine to join two pieces of mesh fabric at the longitudinal edges thereof with the pieces extending in opposite directions from the seam and having a reciprocating and oscillating needle bar, a presser foot and feed dogs, an attachment comprising a base adapted to be secured to the work support before said feed dogs, a shaft carried by said base, a roll on said shaft, said roll being provided with a plurality of projections circumferentially thereof and positioned in accordance with the pattern of the interstices in the mesh fabrics fed thereover to progressively engage the interstices adjacent the respective edge of each piece of fabric and align the pieces in position, means to guide the fabrics in their travel to said aligning roll, and means to guide the fabrics after leaving said aligning roll.

9. For a zig-zag sewing machine to join two pieces of mesh fabric at the longitudinal edges thereof with the pieces extending in opposite directions from the seam and having a reciprocating and oscillating needle bar, a presser foot and feed dogs, an attachment comprising a base adapted to be secured to the work support before said feed dogs, a shaft carried by said base, a roll on said shaft, said roll being provided with a plurality of projections circumferentially thereof and positioned in accordance with the pattern of the interstices in the mesh fabrics fed thereover to progressively engage the interstices adjacent the respective edge of each piece of fabric and align the pieces in position, means to drive the aligning roll shaft from the pulley end of the machine, means to render said driving means inoperative for driving said aligning roll shaft, means to guide the fabrics in their travel to said aligning

roll, and means to guide the fabrics after leaving said aligning roll.

10. For a zig-zag sewing machine to join two pieces of mesh fabric at the longitudinal edges thereof with the pieces extending in opposite directions from the seam and having a reciprocating and oscillating needle bar, a presser foot and feed dogs, an attachment comprising a base adapted to be secured to the work support before said feed dogs, a shaft carried by said base, a roll on said shaft, said roll being provided with a plurality of projections circumferentially thereof and positioned in accordance with the pattern of the interstices in the mesh fabrics fed thereover to progressively engage the interstices adjacent the respective edge of each piece of fabric and align the pieces in position, means to guide the fabrics in their travel to and from said aligning roll, and means to inhibit the edges of said fabrics from overlapping in their travel to and from said aligning roll.

11. For a zig-zag sewing machine to join two pieces of mesh fabric at the longitudinal edges thereof with the pieces extending in opposite directions from the seam and having a reciprocating and oscillating needle bar, a presser foot and feed dogs, an attachment comprising a base adapted to be secured to the work support before said feed dogs, a shaft carried by said base, a roll on said shaft, said roll being provided with a plurality of projections circumferentially thereof and positioned in accordance with the pattern of the interstices in the mesh fabrics fed thereover to progressively engage the interstices adjacent the respective edge of each piece of fabric and align the pieces in position, an arm resiliently mounted on said shaft and means carried by said arm to guide the fabrics in their travel to said aligning roll, said guide having means to prevent the edges of said fabrics from overlapping.

12. For a zig-zag sewing machine to join two pieces of mesh fabric at the longitudinal edges thereof with the pieces extending in opposite directions from the seam and having a reciprocating and oscillating needle bar, a presser foot and feed dogs, an attachment comprising a base adapted to be secured to the work support before said feed dogs, a shaft carried by said base, a roll on said shaft, said roll being provided with a plurality of projections circumferentially thereof and positioned in accordance with the pattern of the interstices in the mesh fabrics fed thereover to progressively engage the interstices adjacent the respective edge of each piece of fabric and align the pieces in position, and means to guide the fabrics in their travel to said aligning roll, said guide being carried by said shaft and having means to prevent the edges of said fabrics from overlapping.

13. For a zig-zag sewing machine to join two pieces of mesh fabric at the longitudinal edges thereof with the pieces extending in opposite directions from the seam and having a reciprocating and oscillating needle bar, a presser foot and feed dogs, an attachment comprising a base adapted to be secured to the work support before said feed dogs, a shaft carried by said base, a roll on said shaft, said roll being provided with a plurality of projections circumferentially thereof and positioned in accordance with the pattern of the interstices in the mesh fabrics fed thereover to progressively engage the interstices adjacent the respective edge of each piece of fabric and

align the pieces in position, means to guide the fabrics after leaving said roll, and means to mount said guide on the presser foot bar.

14. For a zig-zag sewing machine to join two pieces of mesh fabric at the longitudinal edges thereof with the pieces extending in opposite directions from the seam and having a reciprocating and oscillating needle bar, a presser foot and feed dogs, an attachment comprising a base adapted to be secured to the work support before said feed dogs, a shaft carried by said base, a roll on said shaft, said roll being provided with a plurality of projections circumferentially thereof and positioned in accordance with the pattern of the interstices in the mesh fabrics fed thereto to progressively engage the interstices adjacent the respective edge of each piece of fabric and align the pieces in position, a guide beneath which the fabrics pass after leaving said roll, means resiliently mounting said guide on said presser foot bar, and means on said guide to prevent the edges of the aligned fabrics from overlapping.

15. For a zig-zag sewing machine to join two pieces of mesh fabric at the longitudinal edges thereof with the pieces extending in opposite directions from the seam and having a reciprocating and oscillating needle bar, a presser foot and feed dogs, an attachment comprising a base adapted to be secured to the work support before said feed dogs, a shaft carried by said base, a roll on said shaft, said roll being provided with a plurality of projections circumferentially thereof and positioned in accordance with the pattern of the interstices in the mesh fabrics fed thereover to progressively engage the interstices adjacent the respective edge of each piece of fabric and align the pieces in position, a guide beneath which the fabrics pass after leaving said roll, means to mount said guide on the presser foot bar, and means on said guide to prevent the edges of the aligned fabrics from overlapping.

16. A method which comprises simultaneously aligning two pieces of mesh fabric with two opposite edges thereof in abutting relationship and the interstices in substantially matching relationship, and securing said edges together by zig-zag stitching.

17. A method which comprises aligning two pieces of mesh fabric with two opposite edges thereof in abutting relationship, inhibiting said opposite edges from overlapping prior and subsequent to the aligning operation, and securing said edges together by zig-zag stitching.

18. For a zig-zag sewing machine to join two pieces of mesh fabric at the longitudinal edges thereof with the pieces extending in opposite directions from the seam and having a reciprocating and oscillating needle bar, a presser foot and feed dogs, an attachment comprising a base adapted to be secured to the work support before said feed dogs, a shaft carried by said base, a roll on said shaft, said roll being provided with a plurality of projections circumferentially thereof and positioned in accordance with the pattern of the interstices in the mesh fabrics fed thereover to progressively engage the interstices adjacent the respective edge of each piece of fabric and align the pieces in position, a fabric-supporting roll on the aligning roll shaft and spaced from the said aligning roll, means to guide the fabrics in their travel to said aligning roll, and means to guide the fabrics after leaving said aligning rolls.

CHARLES SEAMAN.
